WINDOW

Carl F. Aberle and Henry G. Aberle,
St. Louis, Mo.

Application February 6, 1933, Serial No. 655,313

17 Claims. (Cl. 189—67)

This invention relates to windows, and has special reference to a new arrangement, combination and construction of parts forming the window sashes, and also has reference to a novel 5 type and form of window frame in which the sashes are operatively mounted.

Objects of the invention are to provide improved upper and lower window sashes of the vertically sliding type and mounted in a window 10 frame whereby the sashes are guided in their longitudinal movements; to provide novel guides whereby the sashes are guided in their movements; to provide improved joints between adjacent ends of the sashes and between the sashes 15 and the window frame; to provide means for sustaining and supporting the window sashes in any one of numerous selected adjustments to obtain different types and effects of ventilation and air circulation; to provide a novel arrangement for 20 obtaining an inwardly swinging movement of the sashes to expedite and facilitate the work of cleaning the window panes; to provide improved guides for the window sash weights which sustain and support the window sashes in their 25 different vertical adjustments and which are connected up with the window sashes in such a way that there is no interference or interruption with the free swinging movements of the window sashes for the purpose indicated; and to provide 30 all of the other improved features of construction and arrangements of parts herein disclosed, reference being made to the annexed drawings, in which—

Fig. 1 is a vertical sectional view of a window 35 comprising upper and lower sashes and a frame in which said sashes are mounted.

Fig. 2 is a cross sectional view of the window frame and one of the sashes, showing the construction and arrangement of the weight guides 40 and other features.

Fig. 3 is an enlarged sectional view of one side of the window frame, showing more clearly the arrangement of the sash guides.

Fig. 4 is a side elevation of one of the movable members that operates in one of the sash guides.

Fig. 5 is a view looking toward one side edge of the device shown in Fig. 4, and showing the connection thereof with the window sash.

Fig. 6 is a vertical sectional view similar to Fig. 1, the window sashes being omitted to disclose the guide devices.

Fig. 7 is a cross sectional view on the line 7—7 of Fig. 1, looking in the direction of the arrows.

Fig. 8 is an inner side view of the complete

window, including sashes and frame embodying the present invention.

Fig. 9 is a vertical sectional view of the window frame, the sashes being omitted for comparison with Figs. 10 to 18, inclusive, which show various 60 relative positions of the upper and lower window sashes.

Fig. 19 is a detail view showing the lower portion of the lower window sash in its raised position to permit outward swinging movement of the 65 upper window sash when the latter is in its lowered position.

Fig. 20 is a cross sectional view of the window frame on the line 20—20 of Fig. 19.

Fig. 21 is a cross sectional view of the window 70 frame on the line 21—21 of Fig. 19.

Fig. 22 is an enlarged detail view, showing the pivotal connection of the lower window sash with the frame.

Fig. 23 is a vertical sectional view of modified 75 types of window sashes and frame.

Fig. 24 is a cross sectional view of the window frame and the upper sash of this modified type.

Figs. 25 and 26 are side and side edge views, 80 respectively, of the guide members pivotally connected with the lower ends of the window sashes.

Fig. 27 is an enlarged detail sectional view, showing the guides for the guide devices.

Fig. 28 is a vertical sectional view similar to Fig. 23, the window sashes being omitted to show 85 the guides therefor.

Fig. 29 is a cross sectional view of the window frame, showing other features of the invention.

Fig. 30 is an outer side view of a complete window of this modified construction.

The window frame, shown in Figs. 1 to 22, inclusive, may be constructed principally of sheet metal shaped to form a bottom member having a downwardly and outwardly inclined portion 1 connected with an inner portion 2 by a raised 95 joint forming portion 3. The bottom of the window frame also includes a section of inwardly extended sheet metal forming a lower wall 4 having its outer edge connected with the part 2. Rubber or other elastic supports 5 are attached 100 to the wall 4.

The upper end of this window frame may also be composed of sheet metal shaped to provide a top wall 6 having an inner vertical extension 7 and an upwardly extended portion 8 in connection with its outer edge and engaging a part of the building wall above the window opening. The upper end of this window frame further comprises a section of sheet metal 9 having its outer edge attached to the upward extension 7. 110

- and its outer marginal portion 10 extended upwardly and engaging the wall around the window opening. A bracing device, comprising a section of sheet metal 11, is mounted above the members 6 and 9 and has its outer and inner edges engaging the upper edges of the extensions 8 and 10, respectively. An intermediate portion of the member 9 is swaged upwardly to provide a channel 12.
- 10 The two sides of the window frame are of duplicate construction and like reference numerals are applied to analogous parts of each. Each side of the window frame includes a section of sheet metal shaped and formed to provide an outer exposed portion 13 and an offset inwardly extended portion 14. The outer edge of the portion 13 is engaged with the outer edge of a vertical angular sheet metal member 15, the inner edge of which is connected with one edge 15 of a vertical wall forming plate 16 having its inner edge attached to the inner edge of the part 14 of the frame. A partition plate 17 is attached to the member 15 and extends inwardly therefrom to separate and space apart and guide the window sash weights.
- 20 A channel member 18 is attached to each of the parts 13 and constitutes guides and joint forming members for the window sashes. A channel member 19, in alignment with and in continuation of the channel member 18, may be attached to the upper end portion 6 of the window frame to form a joint at the upper end of the upper window sash.
- 25 A relatively wide channel plate 20 is attached to the upper portion of each side frame member 14 and is spaced inwardly from the guide 18 to permit the upper sash to pass between these guides 18 and 20. A channel guide 21 is attached to the side frame member 14 and spaced inwardly from the guide 20, the space separating the guides 20 and 21 being approximately equal to the width of the channel 12 (Fig. 1). The lower ends of these guides 20 and 21 are slightly above the lower end of the upper window sash and above the upper end of the lower window sash when the window is closed in order to permit inward swinging movement of the lower window sash, as will be understood by reference to Fig. 1, and also permit inward swinging movement of the upper window sash when said upper window sash is in its down position, as will be understood by reference to Fig. 18. An abutment guide member 22 is mounted on a pivot 23 in connection with each side frame member 14 and is constructed so that the lower end thereof can be swung outwardly and upwardly from vertical position to the positions shown in Figs. 17 and 18, which will permit the upper end of either window sash to be swung inwardly when the window sash is in its lower position. An elastic bumper 24, in connection with the outer side of the pivoted guide 22, constitutes an abutment for the upper end of either window sash to limit extent of inward swinging movement of the window sash when the pivoted guide is in its vertical position (Fig. 19). A spring actuated detent 25, in connection with the pivoted guide 22, is adapted to engage in indentations 26 in the frame side member 14 to hold the pivoted guide 22 in its vertical or raised position, as desired.
- 30 Each side frame member 14 is formed with a vertical slot 27 spaced inwardly from the guide 13 and with an inwardly and upwardly extending slot 28 having its lower end opening into the lower portion of the slot 27. A single slot 29 ex-

tends downwardly in continuation of the slots 27 and 28 and has an upwardly and inwardly curved end portion 30 separated from the slot 29 by a portion 31 of the side frame member 14.

35 A tubular guide 32 is attached to the outer side of the lower portion of the side frame member 14 and has a flange 33 projecting through the slot 27 along the inner edge of said slot in continuation of the inwardly extended flange 34 of an angle member attached to the side frame member 14 above the upper end of the slot 27 and between the guides 18 and 20. The flange 34 is separated from the outer edge of the guide 20 by an intervening space 35.

40 A curved tube 36 is attached to the outer side of each side frame member 14 and has an opening to the slot 28 analogous to the opening from the tube 32 to the slot 27.

45 The sash for the lower window comprises a channel member 37 forming the lower end of the sash and supporting a flange or plate 38 adapted to seat upon the raised joint forming portion 3 at the lower end of the window frame and a downwardly extended flange or strip 39 adapted to seat against the outer side of said raised portion 3 and form therewith an appropriate weatherproof and tight joint. A flange 40 extends upwardly from the channel member 37.

50 The upper end of the lower sash includes an upwardly open channel member 41 having a downwardly extended flange 42 in vertical alignment with the flange 40 (Fig. 1).

55 The two vertical side members of the lower sash are metallic channels having laterally extended outer flanges 43 adapted to engage against the inner surfaces of the guides 18, and wider inner flanges 44 designed and adapted to operate close to the frame portions 14. These vertical channel members are rigidly connected with the ends of the sash member 37 and 41 to form a strong window sash, and said vertical channel members are provided with flanges 45 in alignment with the flanges 40 and 42. Putty 46, appropriately applied to the sash including the flanges 40, 42 and 45, secures the window pane 47 in the sash and provides weather-proof and water-proof joints.

60 A trunnion 48 (Fig. 5) projects laterally from each end of the lower sash member into the lower ends of the slots 29 in the closed position of the lower sash. In the lower position of the lower sash, a weather-proof joint is formed with the raised joint forming portion 3. A guide block 49 is pivoted on each trunnion 48 at the concealed side of the frame portions 14 and within the tubes 36. These guide blocks support rollers 50, which operate against the side walls of the tubes 36 and thereby guide the lower sash in its upward and downward movements. Cords 51 extend over pulleys 52 rotatively supported by brackets 53 in the spaces between the partitions 17 and the plates 16 and are connected with weights 54 operative in said spaces. These weights will support the lower window in any of its raised positions and will facilitate and expedite the operation of the lower window. The upper end of the lower window may be swung inwardly against the bumpers 24 (Figs. 11 and 12), and the lower window may then be raised to any of the ventilating positions shown in Figs. 13 to 16, inclusive. Or the guides 22 may be swung outwardly and upwardly to the position indicated in Fig. 17, and the lower window may be swung inwardly and downwardly onto the elastic supports 5 (Fig. 17) and the trunnions 48 engaged in the upwardly ex-

tended slots 30 against the abutment portions 31. In this way, the lower window will be supported in an approximately horizontal position and prevented from tilting by engagement of the trunnions 48 in the slots 30 and against the abutments 31.

After the upper end of the lower window sash is swung outwardly against the bumpers 24, said lower window sash may be moved upwardly, the flanges 44 operating between the guides 20 and 21, as indicated in Figs. 2 and 7. In this upward movement of the lower window sash, the trunnions 48 move through the slots 29 and into and along the slots 28, the rollers 50 of the guides 49 operating against the walls of the tubes 36.

The upper window sash comprises a lower channel member 55 having a depending outer flange 56 designed and adapted to lie against the outer side of the upper end member 41 of the lower sash (Fig. 1) and an inner flange 57 arranged to lie against the inner flange of said member 41. The upper end member of the upper sash comprises a channel member including an outer flange 58 forming joint with the guides 18 and 19 and an inner flange 59 overlapping the upper frame portion 7 and extending into a space between said frame portion 7 and an attached plate 60. The sides of the upper sash are duplicates, each comprising a channel member having an outer flange 61 operating against the guides 18 and an inner flange 62 operating against the flanges 33 and against the outer sides of the guides 20. The lower member of the upper sash has an upwardly extended flange 63 in alignment with a downwardly extended flange 64 in connection with the upper end member of the sash and in alignment with inwardly extended flanges 65 in connection with the side members of the sash. Putty 66, appropriately applied to these sash members and to the flanges 63, 64 and 65, will form a hermetic joint and secure the window pane 67 in position.

Trunnions 68 project from the opposite ends of the lower member 55 into the slots 27 and are connected with guides 69, like the guides 49, and are equipped with rollers 70, the same as the rollers 50. These guides 69—70 operate in the tubes 32 and are connected with window sash cords 71 extending over pulleys 72 supported by brackets 73. The cords 71 are connected with weights 74 operating at the opposite sides of the partition 17 from the weights 54.

After raising the lower sash to the position shown in Fig. 18, the upper sash may be moved downwardly to the position previously occupied by the lower sash, the guides 22 swung upwardly and outwardly, and the upper end of the lower sash may then be swung inwardly and downwardly onto the elastic supports 5 and the trunnions 68 placed in the inwardly and upwardly extended slots 30 against the abutments 31. In this position, the outer surface of the window pane 67, or a plurality of such panes as shown in Fig. 5, may be cleaned without difficulty.

The upper and lower sashes may be moved to the various relative ventilating positions to control circulation of ventilating air, some of such positions being shown in Figs. 11 to 16, inclusive, and the path of the circulating air being indicated by arrows.

A closure plate 75 may be mounted in the channel member 41 to prevent the lodgment of particles of foreign matter in said member 41.

The invention illustrated in Figs. 23 to 30, inclusive, varies somewhat in the form of the parts

from the invention above described, but equal advantages may be obtained as by use of the other form.

This modified form of window frame comprises a lower metallic frame member including an inwardly extended portion 76, a downwardly and outwardly inclined portion 77, and a raised joint forming portion 78. These parts may be made of a single piece of material.

The upper frame member comprises a part 79 having along its outer edge a downwardly extended portion 80 connected with a joint forming portion 81 by a wall forming a groove 82 and a portion 83 connecting the wall of the groove with said joint forming portion 81. The joint forming portion 81 has an extended portion 84 connected with a superimposed plate 85 to which the part 79 is also attached.

The sides of the frame are of duplicate construction, each comprising a portion 86 connected with a vertical guide 87 in extended continuation of or in alignment with the joint forming portion 81 by a joint forming connection 88. The inner edge of each part 86 is attached to connecting members 89, one or both of which are connected with a member 90 having its outer edge attached to an extension of the guide 87.

The parts 86 are formed with vertical slots 91, from which upwardly and inwardly inclined slots 92 extend. Said slots 91 and 92 are extended to slots 93 opening to upwardly and inwardly inclined slots 94, at the outer sides of which are abutments 95.

Guides 96 are attached to the frame portions 86 parallel with and spaced from the joint forming parts 88, and other guides 97 are in rigid connection with the parts 86 and spaced inwardly therefrom. At the lower ends of the guides 97, we mount the pivoted guide members 22 in the manner already described.

Tubes 98 are attached to the outer sides of the lower portions of the parts 86 opposite the slots 91 and curved tubes 99 are mounted opposite the slots 92.

The lower end members of both window sashes 120 are alike, each comprising a tube 100 irregular in cross section having in its under side a groove 101 adapted to receive the upwardly extended joint forming portion 78 and having in connection with its outer side a downwardly extended flange 102. The downwardly extended flange 102 of the lower sash cooperates with the upper wall of the upwardly extended joint forming portion 78 to form a weather-proof joint, while the downwardly extended flange 102 at the lower end 130 of the upper sash cooperates with the upper end 125 of the lower sash to form a tight joint. A groove 103 extends along the upper side of each tube 100.

The upper end of the lower sash comprises a tube 104 that is irregular in cross section and 135 having on its inner side an upwardly extended flange 105 and along its inner edge a downwardly extended flange 106. An angular strip 107 is attached to the under side of the tube 104 and spaced from the flange 106.

The side members 108 of both sashes are alike, each being in cross section an irregular tube having along its outer side a dovetail joint forming portion 109 for cooperation with the joint forming parts 99 to obtain weather-proof joints. 145 Each tube 108 has an inwardly extended flange 110. The tubes 108 of the lower sash are attached to the ends of the tubes 100 and 104, respectively. The lower ends of the tubes 108 of the upper sash are attached to the ends of the tube 100 and 150

the upper ends of said tubes 108 are attached to the ends of an irregular tube 111 having an extended portion 112 adapted to engage in the groove 82.

- 5 Window panes 113 have their lower edges embedded in putty in the grooves 103 and their vertical and upper edges held in place by fasteners 114 cooperating with the flanges 110 on the side members of the sash, and a similar flange 115 on
10 the upper sash member 111 and with putty 116 applied as shown.

Trunnions 117 project from the ends of the sash members 100 through the slots 91 and are pivotally connected with blocks 118 in the tubes 98 and 99 and equipped with rollers 119 to facilitate their operation. Window sash cords 120 are connected with the blocks 118 and extend over pulleys 121 and are connected with weights 122 operating in spaces at the sides of the window frame, as shown.

These window sashes may be turned over to approximately horizontal positions to rest the panes 113 on the elastic supports 123, corresponding to the supports 5.

- 25 It is now clear that these window sashes of this modified construction may be moved to any of the relative adjustments and positions indicated in the annexed drawings in order to provide for ventilation and to control and direct the passage 30 of the ventilating air.

Our improved window and window frame may be made of any appropriate material, preferably of non-corrodible metal or alloy, so as to provide an enduring construction. Better ventilating effects may be obtained by directing and controlling the air currents than by use of windows of ordinary construction incapable of being adjusted and positioned as herein disclosed. The construction, arrangement and form of the parts may be widely varied within the scope of equivalent limits without departure from the nature and principle of the invention. We do not restrict ourselves in any unessential particulars, but what we claim and desire to secure by Let-

45 ters Patent is:

1. In a window, a frame having upwardly diverging slots through opposite sides of the frame, sash guides in connection with said frame, vertically movable sashes mounted in said frame and 50 cooperating with said guides to form joints, trunnions in connection with the lower end of each of said sashes projecting through said slots, guide blocks connected with said trunnions at the concealed sides of said frames, means other than 55 said slots guiding said blocks, and window sash weights connected with said guide blocks for counterbalancing said sashes.

60 2. In a window, a frame having a single downwardly and inwardly extended slot at each side of its lower end opening into the lower ends of vertical slots and upwardly and inwardly inclined slots through opposite sides of the frame, guide elements attached to the concealed sides of said frame adjacent to said slots, upper and lower window sashes mounted in said frame, trunnions in connection with the lower end of each of said sashes projecting through said vertical slots in the closed positions of said sashes, means in connection with said trunnions that project from the lower end of said lower sash for guiding said lower sash trunnions along said upwardly and inwardly inclined slots, window sash weights at the concealed sides of said frame, and flexible connections connecting said weights respectively

with said respective trunnions at the concealed sides of said frame.

3. In a window, a frame having a single downwardly and inwardly extended slot at each side of its lower end opening into the lower ends of vertical slots and upwardly and inwardly inclined slots through opposite sides of the frame, guide elements attached to the concealed sides of said frame adjacent to said slots, upper and lower window sashes mounted in said frame, trunnions in connection with the lower end of each of said sashes projecting through said vertical slots in the closed positions of said sashes, means in connection with said trunnions that project from the lower end of said lower sash for guiding said lower sash trunnions along said upwardly and inwardly inclined slots, window sash weights at the concealed sides of said frame, flexible connections connecting said weights respectively with said respective trunnions at the concealed sides of said frame, and construction at the lower ends of said vertical slots cooperating with said trunnions to support either of said sashes in inwardly extended position. 80 85 90 95

4. In a window, a metallic frame having a pair 100
of slots through each side of the frame, each pair
of said slots opening into a single downwardly
and inwardly extended slot at the lower end of
said frame, window sashes mounted in said
frame and each composed of hollow metallic end 105
and side members cooperating with said frame
and with each other to provide sealed joints,
trunnions projecting from the lower ends of said
sashes respectively through said slots, window
sash weights at the concealed sides of said frame 110
operatively connected with said trunnions at the
concealed sides of said frame, and movable abut-
ments for supporting either of said sashes in-
clined inwardly and upwardly when the respec-
tive sashes are at the lower end of said frame, 115
said abutments being movable to permit said
sashes to be swung inwardly and downwardly
approximately to horizontal position.

5. In a window, a metallic frame having a pair of slots through each side of the frame, each pair of said slots opening into a single downwardly and inwardly extended slot at the lower end of said frame, window sashes mounted in said frame and each composed of hollow metallic end and side members cooperating with said frame and with each other to provide sealed joints, trunnions projecting from the lower ends of said sashes respectively through said slots, window sash weights at the concealed sides of said frame operatively connected with said trunnions at the concealed sides of said frame, movable abutments for supporting either of said sashes inclined inwardly and upwardly when the respective sashes are at the lower end of said frame, said abutments being movable to permit said sashes to be swung inwardly and downwardly approximately to horizontal position, and construction at the lower ends of said slots cooperating with said trunnions and said weights to limit extent of upward movement of the lower ends of said sashes when said sashes are in approximately horizontal position. 140

6. In a window, a metallic frame having slots in its opposite sides, the slots at each side of said frame opening at their lower ends into a single downwardly and inwardly extended slot, upper and lower sashes movable upwardly and downwardly mounted in said frame, projections in connection with said sashes extending through said slots to the concealed sides of said frame 145 150

and guide means on the concealed sides of said frame cooperating with said projections to guide said sashes respectively in their upward and downward movements.

5. 7. In a window, a metallic frame having slots in its opposite sides, the slots at each side of said frame opening at their lower ends into a single downwardly and inwardly extended slot, upper and lower sashes movable upwardly and downwardly mounted in said frame, projections in connection with said sashes extending through said slots to the concealed sides of said frame, guide means at the concealed sides of said frame for guiding said lower sash upwardly and inwardly with respect to said upper sash, and devices connected at the concealed sides of said frame with said projections that extend from said lower sash for supporting said lower sash in different positions with respect to said upper sash.

20. 8. In a window, a metallic frame having slots in its opposite sides, the slots at each side of said frame opening at their lower ends into a single downwardly and inwardly extended slot, upper and lower sashes movable upwardly and downwardly mounted in said frame, projections in connection with said sashes extending through said slots to the concealed sides of said frame, guide means at the concealed sides of said frame for guiding said lower sash upwardly and inwardly with respect to said upper sash, devices connected at the concealed sides of said frame with said projections that extend from said lower sash for supporting said lower sash in different positions with respect to said upper sash, and construction at the lower ends of said slots for cooperating with said projections on said respective sashes to support said respective sashes in inwardly extended positions.

9. In a window, a frame having a single downwardly and inwardly extended slot at each side of its lower end and each of said slots opening into two upwardly diverging slots, means holding those portions of the frame which are between said upwardly diverging slots in rigid relationship with the remainder of the frame, vertically movable upper and lower sashes mounted in said frame, trunnions in connection with the lower end of each of said sashes projecting through said slots for movement therealong from and to positions in which said sashes are located one below the other, means for supporting said lower sash in a position in which the lower end thereof is above the plane of the upper end of the upper sash when the upper sash is in the lowermost position to which it is movable and in which the upper sash may be swung inwardly below and beyond the lower end of the lower sash.

10. In a window, a frame having a single downwardly and inwardly extended slot at each side of its lower end and each of said slots opening into two upwardly diverging slots, means holding those portions of the frame which are between said upwardly diverging slots in rigid relationship with the remainder of the frame, vertically movable upper and lower sashes mounted in said frame, trunnions in connection with the lower end of each of said sashes projecting through said slots for movement therealong from and to positions in which said sashes are located one below the other, window sash weights at the concealed sides of said frame, cords connected with said weights and with said trunnions at the concealed sides of said frame, and pulleys at the upper end of said frame supporting said cords respectively.

11. In a window, a metallic frame having slots in its opposite sides, upper and lower sashes movable upwardly and downwardly mounted in said frame, trunnions in connection with the lower ends of said sashes respectively extending through said slots to the concealed sides of said frame, sash weights at the concealed sides of said frame connected with the trunnions at the concealed sides of said frame, said lower sash being movable upwardly to a position in which its lower end is above the upper end of the upper sash when the upper sash is in the lowermost position to which it is movable, thereby leaving the upper sash free for inward swinging movement below and beyond the lower sash, and means for locking the upper sash in the position in which it is swung inwardly as aforesaid.

12. In a window, a metallic frame having a single downwardly and inwardly extended slot at each side of its lower end and having two upwardly diverging slots opening into the upper end of each of said single slots, means holding those portions of the frame which are between said upwardly diverging slots in rigid relationship with the remainder of the frame, vertically movable upper and lower sashes mounted in said frame for adjustment in vertical alinement to close said frame, trunnions in connection with the lower end of each of said sashes projecting through said slots for movement therealong from and to positions in which said sashes are located in vertical alinement, sash weights at the concealed sides of said frame connected with said trunnions at the concealed sides of said frame, and a raised portion of said frame into which the upper end of said lower sash is movable to position in which the lower end of said lower sash is above the upper end of the upper sash when the upper sash is in the lowermost position to which it is movable and in which position the upper sash may be swung inwardly below and beyond the lower end of the lower sash and said trunnions on said upper sash may enter the inwardly extended portions of said slots to lock said upper sash against upward movement.

13. In a window, a metallic frame having a single downwardly and inwardly extended slot at each side of its lower end and having two upwardly diverging slots opening into the upper end of each of said first named slots, means holding those portions of the frame which are between said upwardly diverging slots in rigid relationship with the remainder of the frame, vertically movable upper and lower sashes mounted in said frame, trunnions in connection with the lower end of each of said sashes projecting through and movable along said diverging slots respectively into said inwardly extended slots to lock said sashes respectively against upward movement, and means at the concealed sides of said frame connected with said trunnions on said lower sash for supporting said lower sash in a raised position in which the lower end thereof is above the plane of the upper end of the upper sash when the upper sash is in the lowermost position to which it is movable and in which position the upper sash may be swung inwardly below and beyond the lower end of the lower sash and said trunnions on said upper sash extended into said inwardly extended slots.

14. In a window, a frame having a single downwardly and inwardly extended slot at each side of its lower end and having two upwardly diverging slots opening into the upper ends of each of said single slots, means holding those por-

tions of the frame which are between said upwardly diverging slots in rigid relationship with the remainder of the frame, vertically movable upper and lower sashes mounted in said frame for adjustment in vertical alignment to close said frame, trunnions in connection with the lower end of each of said sashes projecting through said slots for movement therealong from and to positions in which said sashes are located in vertical alignment and to positions in which said trunnions are engaged in said downwardly and inwardly extended slots, sash weights at the concealed sides of said frame connected with said trunnions at the concealed sides of said frame, said lower sash being movable upwardly to a position in which its lower end is above the upper end of the upper sash when the upper sash is in the lowermost position to which it is movable, thereby leaving the upper sash free for inward swinging movement below the lower sash, and means for supporting the upper sash inclined inwardly below the lower sash when the upper sash is down and the lower sash is in its upper position.

15. In a window, a frame having diverging slots in its opposite sides, means holding those portions of the frame which are between said diverging slots in rigid relationship with the remainder of the frame, upper and lower sashes movable upwardly and downwardly mounted in said frame, trunnions in connection with the lower ends of said sashes respectively extending through said slots to the concealed sides of said frame connected with the trunnions at the concealed sides of said frame, said lower sash being movable upwardly to position in which its lower end is above the upper end of the upper sash when the upper sash is in the lowest position to which it is movable, thereby leaving the upper sash free for inward swinging movement below and beyond the lower sash, and means for preventing upward movement of the

lower end of said upper sash when said upper sash is swung inwardly beyond the lower sash as aforesaid.

16. In a window, a frame having a single downwardly and inwardly extended slot at each side of its lower end and having two upwardly diverging slots opening into the upper end of each of said single slots, means holding those portions of the frame which are between said upwardly diverging slots in rigid relationship with the remainder of the frame, upper and lower sashes movable upwardly and downwardly mounted in said frame, trunnions in connection with the lower ends of said sashes respectively extending through said slots to the concealed sides of said frame, said trunnions on each sash being movable into said single slots when the other sash is out of the way, and window sash weights at the concealed sides of said frame connected with said trunnions at the concealed sides of said frame.

17. In a window, a frame having a single downwardly and inwardly extended slot at each side of its lower end and having two upwardly diverging slots opening into the upper end of each of said single slots, means holding those portions of the frame which are between said upwardly diverging slots in rigid relationship with the remainder of the frame, upper and lower sashes movable upwardly and downwardly mounted in said frame, trunnions in connection with the lower ends of said sashes respectively extending through said slots to the concealed sides of said frame, said trunnions on each sash being movable into said single slots when the other sash is out of the way, and window sash weights at the concealed sides of said frame connected with said trunnions at the concealed sides of said frame, each of said sashes being movable inwardly to approximately horizontal position when the other sash is in its upper position.
